CLAIM

The ornamental design for a surgical system instrument interface sterile adapter, as shown and described.

DESCRIPTION

FIG. 1 is a top perspective view of a surgical system instrument interface sterile adapter of our new design;

FIG. 2 is a bottom perspective view thereof;

FIG. 3 is a left side view thereof;

FIG. 4 is a front view thereof;

FIG. 5 is a right side view thereof;

FIG. 6 is a rear view thereof;

FIG. 7 is a top view thereof; and,

FIG. 8 is a bottom view thereof.

The shade lines in the Figures show contour and not surface ornamentation.

The broken lines in the Figures illustrate unclaimed portions and exemplary environmental structure of the surgical system instrument interface sterile adapter and form no part of the claimed design.
